UNITED STATES PATENT OFFICE.

CLAES W. BOMAN, OF NEW YORK, N. Y., ASSIGNOR TO THE EAGLE PENCIL COMPANY, OF NEW YORK.

DESIGN FOR A PEN-TIP.

SPECIFICATION forming part of Design No. 20,157, dated September 23, 1890.

Application filed August 20, 1890. Serial No. 363,148. Term of patent 7 years.

To all whom it may concern:

Be it known that I, CLAES W. BOMAN, of the city, county, and State of New York, have invented a new and original Design for Pen-Tips, of which the following is a specification.

What is known in the trade as a "pen-tip" is that portion of a pen-holder in which the pen is inserted and held.

My new design for a pen-tip is illustrated in the accompanying drawing.

It consists of a larger cylindrical portion *a*, having at the front an annular bevel *b* between the larger cylindrical portion *a* and the smaller cylindrical portion *c*, while at its front it ter-

minates in a somewhat abrupt flare *d*. Just 15 in advance of the contracted end of the bevel *b* is an annular bead *e*.

What I claim, and desire to secure by Letters Patent, is—

The design for pen-tips, as shown.

In testimony whereof I have hereunto signed my name in the presence of two subscribing witnesses.

CLAES W. BOMAN.
